UNITED STATES PATENT OFFICE

133,782

DESIGN FOR A SCREW DRIVER

William H. Pfeiffer, Seattle, Wash.

Application May 13, 1942, Serial No. 106,882

Term of patent 3½ years

To all whom it may concern:

Be it known that I, William H. Pfeiffer, a citizen of the United States, residing at Seattle, in the county of King and State of Washington, have invented a new, original, and ornamental Design for a Screw Driver, of which the following is a specification, reference being had to the accompanying drawing, forming part thereof.

In the aforesaid drawing, the figure is an elevational view of a screw driver, showing my new design.

The portion of the screw driver not disclosed is substantially the same as that shown in the drawing.

I claim:

The ornamental design for screw driver, as shown and described.

WILLIAM H. PFEIFFER.
